UNITED STATES PATENT OFFICE.

ADDIE H. HORNSBY, OF OMAHA, NEBRASKA.

WASHING-MACHINE.

1,134,613.

Specification of Letters Patent. Patented Apr. 6, 1915.

Application filed November 9, 1911, Serial No. 659,405. Renewed August 17, 1914. Serial No. 857,431.

To all whom it may concern:

Be it known that I, ADDIE H. HORNSBY, a citizen of the United States, residing at Omaha, in the county of Douglas, State of Nebraska, have invented certain new and useful Improvements in Washing-Machines; and I do hereby declare the following to be a full, clear, and exact description of the invention, such as will enable others skilled in the art to which it appertains to make and use the same.

This invention relates to an improvement in washing machines of the agitator type.

The principal object of the invention is to provide a novel form of mechanism for reciprocating the agitator.

Another object of the invention is to provide a novel means associated with the agitator for drawing air into the machine below the clothes upon the up stroke of said agitator.

A further object of the invention is to provide a washing machine of the character described which is composed of a minimum number of parts, is simple in construction and is therefore cheap to manufacture.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction within the scope of the claims, may be resorted to without departing from the spirit or sacrificing any of the advantages of the invention.

In the drawing: Figure 1 is a side elevation, partly in section, showing a machine constructed in accordance with my invention, Fig. 2 is a vertical sectional view through the same, Fig. 3 is a top plan view of Fig. 1, Fig. 4 is a detail horizontal sectional view taken on the line 4—4 of Fig. 2, Fig. 5 is a detail sectional view taken on the line 5—5 of Fig. 2, Fig. 6 is a detail sectional view through the pinions, Fig. 7 is a plan view of one of the sections of the plunger rod.

Like reference numerals designate corresponding parts in all the figures of the drawings.

Referring to the drawings, the invention comprises a receptacle 5 having a bottom 6 and an open end 7. Associated with said

upper end is a top 8 which is centrally formed with a circular opening 9. Formed in the top 8 is a door 10, which is connected to said top by means of hinges 11. Centrally disposed within the receptacle is an open ended cylinder 12 having its wall formed with a plurality of openings 13. The lower end of the cylinder is seated upon the bottom 6 of the receptacle, and the upper end thereof projects outwardly through the opening 9 of the top 8. A frusto-conical shell 14 is disposed around the lower end of the cylinder 12, and is formed with a plurality of small perforations 15.

Mounted upon the top 8 is a pair of opposed inverted U-shaped brackets 16 and 17 respectively, each bracket consisting of spaced legs 18—18, and the former including an intermediate and outwardly bowed leg 19. Mounted in the eight portions 20 of said brackets is a bolt 21 constituting an axle, and rotatably mounted on the end thereof and outside the bracket 17 is a wheel 22 which is formed with an internal gear 23. The rim of this wheel is formed with a circumferential groove 24 adapted to be engaged by a belt or other suitable driving means. A crank handle 25 is also secured to the wheel, so that the same may be operated by hand should it be so desired.

Disposed between the brackets 16 and 17 is a plunger rod designated as a whole by the reference numeral 26. This rod is formed of spaced sections 27—27, each being formed on the outer face with a plurality of teeth 28. These sections are disposed on opposite sides of the axle 21, and are connected at their upper ends by means of a plate 29. The lower ends of the sections are each formed with a reduced threaded extremity 30, which is projected through a suitable opening formed in a plate 31. Formed in this plate between said openings is a central opening wherethrough projects the upper end of the neck 32 of a funnel 33, said funnel being adapted to be reciprocated within the cylinder 12, as will be hereinafter more fully described. The mouth of the funnel is provided around its periphery with a packing 33^a which closely engages the inner wall of the cylinder 12. Disposed around the neck 32 of the funnel and below the plate 31 is a second plate 31^a and these plates are connected by a plurality of bolts 34.

In order to reciprocate the plunger rod 26, there are mounted on the legs 18 of the

- bracket 16 and on opposite sides of said rod, stub axles 35—35. Rotatably mounted upon each axle is a single casting forming a pinion 36 and a mutilated gear 37, said pinion 5 and gear being connected by a sleeve 38 which is journaled upon said axle. The pinions 36 are arranged to always mesh with the internal gear 23 of the wheel 22, while the mutilated gears 37 are respectively 10 adapted to alternately engage the teeth 28 of the plunger rod 26. It will thus be observed that when the wheel 23 is rotated, the pinions 36 are caused to rotate and consequently the mutilated gears 37 alternately 15 mesh with the teeth of the plunger rod to cause the latter to reciprocate. It will furthermore be observed that when the plunger rod 26 reciprocates, the funnel 33 will be carried therewith.
- 20 Disposed within the bottom of the cylinder 12 and extending laterally therefrom is a pipe 38 having a series of small perforations 39 formed therein. This pipe projects outwardly beyond the shell 14, and is 25 connected to a plurality of pipe sections 40, the upper section projecting through an opening 41 formed in the top 8 of the machine. Secured to the upper section is a detachable section 42, which by means of an 30 elbow 43 is connected to a horizontal section 44, and this last section is connected by means of an elbow 45 to a depending section 46 adapted to register with and to be slidably engaged by the upper end of the neck 35 32 of said funnel 33.
- Disposed within the receptacle 5 around the cylinder 12 is a follower 47, which is 40 preferably formed of mesh wire or the like, and is adapted to be supported by the clothes within the receptacle, said clothes being placed within the receptacle 5 around the cylinder 12.
- 45 In operation, after the funnel 33 is moved downwardly by the mechanism above described, water will be forced from the in-

terior of the cylinder 12 through the openings 13 thereof and against the clothes. When the funnel is moved upwardly, air will be drawn in through the pipe sections 44, 42, 40, 38 and through the openings 39 50 of the latter and into the cylinder 12, so that on the following downward movement of the funnel, the said air will be caused to pass outwardly through the openings 13 of the cylinder 12 and commingle with the 55 water and clothes around said cylinder, thereby keeping the water in an agitated condition. It will also be observed that when the funnel is moved upwardly, the water will be drawn downwardly through 60 the clothes by the suction created by the funnel. This water will be drawn into the bottom of the cylinder through the perforations thereof, and this water will subsequently pass out from the cylinder through 65 the intermediate perforations.

What is claimed is:

1. In a washing machine, a receptacle, a perforated cylinder within the receptacle, a plunger reciprocable within the cylinder and means associated with the plunger whereby downward movement thereof will introduce air in the bottom of the cylinder.
2. In a washing machine, a receptacle, a perforated cylinder within the receptacle, a 75 plunger comprising an inverted funnel, a pipe disposed within the receptacle and having one end perforated and disposed in the bottom of the cylinder and having its other end projecting downwardly axially of the 80 cylinder and telescopically slidably engaging the neck of the funnel and means for reciprocating the funnel.

In testimony whereof, I affix my signature, in presence of two witnesses.

ADDIE H. HORNSBY.
